TURNING DEVICE FOR ROTATABLE SHAFTS
Earl E. Bailey, 814 Lyngrove Drive, Houston, Tex.
Filed Oct. 14, 1960, Ser. No. 62,567
12 Claims. (Cl. 123—179)

This invention relates to a turning device for a rotatable shaft and, more particularly to a spring starting mechanism for an internal combustion motor of the type having a rotatable shaft which may be utilized to spin the motor and start it in operation.

Many internal combustion engines of a low horsepower output are equipped with a standard hand-operated pull cord by means of which an operator spins the motor shaft to start the engine. The hand-operated pull cord has many disadvantages, which have inspired devices that may be secured to the engine to start same as a substitute for the hand-operated pull cord. In general, these mechanisms are of the type having a spring which may be wound to a desired tension and then released to spin the motor shaft to start the engine. At the present time these mechanisms have met with a favorable reception by users of small internal combustion engines; however, even these mechanisms have certain disadvantages. The most major one is that the spring must be reset manually.

A number of mechanisms featuring a spring which may be wound and selectively released to spin the motor shaft to start an engine have been proposed, which also include some means of using the engine after it is operating to rewind the spring. These mechanisms have featured fairly complex mechanical elements which were found necessary to automatically control the resetting of the spring after it has been utilized to start the engine. The automatic control is usually provided by a timing device that determines the number of turns the spring is wound. In general, the spring starting mechanisms having automatic resetting features have required a plurality of shafts or their equivalents with the result that the mechanism was complex mechanically and difficult to manufacture economically. These features prevented their acceptance by users of the internal combustion engine as a substitute for the type of spring starting mechanisms having manual spring resetting features. An additional disadvantage resides in that the resetting of the spring in such mechanisms is not a positive operation, i.e., the drive connecting means with which the winding mechanism was connected to the engine shaft did not positively engage or disengage and resulted in chattering of clutch members, or the like, and naturally resulted in accelerated wear and destruction of such drive connecting means.

The above defects have, in general, limited the known spring starting mechanisms to those in which the spring is rewound manually and therefore usable only on small internal combustion engines.

It is therefore an object of the present invention to provide a mechanical turning device for a rotatable shaft that is simple to operate, durable, compact and inexpensive to construct, and that is especially suited for use in starting internal combustion engines, large or small.

Another object is to provide a satisfactory spring starting mechanism for internal combustion engines, which after being set can be operated to start such engine and after the engine is operating through movement of the spring to be automatically reset for future use.

A further object is to provide a spring starting mechanism for internal combustion engines that is positive in its operation, both in starting such engine and after the engine is operating in the automatic resetting of the spring for future use.

Another further object is to provide in spring starting mechanisms fulfilling the preceding objects, a means

2

whereby the spring may be reset manually should the engine fail to start.

Another object is to provide a spring starting mechanism for internal combustion engines in accordance with the preceding objects that is easily attachable to existing internal combustion engines and does not require permanent structural modifications of such engines.

These and other objects of the invention will become apparent from the following description when read in conjunction with the accompanying drawings in which:

FIG. 1 is a side elevational view of a rotary type lawn mower on which the turning device of the present invention is mounted;

FIG. 2 is enlarged side elevational view partially in section showing the turning device of FIG. 1 in greater detail;

FIG. 3 is a sectional view taken along 3—3 of FIG. 2;

FIG. 4 is a sectional view similar to FIG. 3 showing the operating plunger in spring locking position.

FIG. 5 is a partial sectional view taken along line 5—5 of FIG. 3;

FIG. 6 is a partial sectional view taken along line 6—6 of FIG. 3;

FIG. 7 is a partial sectional view taken along line 7—7 of FIG. 3;

FIG. 8 is a partial sectional view taken along line 8—8 of FIG. 3;

FIG. 9 is a partial sectional view taken along line 9—9 of FIG. 3;

FIG. 10 is a partial sectional view taken along line 10—10 of FIG. 3;

FIG. 11 is a partial sectional view taken along line 11—11 of FIG. 3;

FIG. 12 is a sectional view taken along line 12—12 of FIG. 2;

FIG. 13 is a sectional view taken along line 13—13 of FIG. 2; and

FIG. 14 is an exploded perspective view illustrating the snap action means of the present invention and the clutch shifting fork that engages and disengages the clutch parts.

For the purpose of describing the present invention, the turning device will be illustrated and described in conjunction with its use for rotating the crankshaft of an internal combustion engine of the type commonly used on rotary lawn mowers, such as illustrated in FIG. 1. It is to be understood, however, that the turning device may be used to rotate the rotatable shafts of other types of devices where it is desired to use the turning device to initially rotate a rotatable shaft and after the shaft is rotating due to some other power source, to use the shaft to restore the turning device to a condition whereby it may be used again.

For convenience in the description of the present invention, the turning device will be described as being comprised of Four Basic Elements, all of which, however, are combined into a unitary device. These elements are:

(1) A spring case stationary with respect to the rotatably mounted a spring shaft about which a spring is positioned within the case and arranged so that the spring may unwind to rotate the spring shaft in one direction and rotation of the shaft in the other direction will rewind said spring, and means connected to the spring shaft whereby a driving connection may be made between the spring shaft and rotatable shaft for rotating the last-mentioned shaft in said one direction;

(2) A rewinding means connected to the spring shaft for rotating the spring shaft in a direction reverse to said one direction to wind the spring;

(3) A clutch means interposed between the rewinding means and the rotatable shaft whereby it may be engaged to provide a drive connection between the rewinding

means and the rotatable shaft so that the spring may be rewound; and

(4) A clutch engaging means connected to the spring intermediate its ends and adapted to engage and disengage such clutch means in response to movement of the spring as its tension is changed during winding and unwinding, whereby the clutch engagement means will automatically engage the clutch means as the spring is unwound so as to effect a rewinding of the spring, and will automatically disengage the clutch means as the spring becomes nearly fully wound. The basic elements will be described in their above-listed order for convenience and in an effort to provide a more clear description of the present invention.

Reference is now had to FIG. 1 of the drawings wherein, for the purposes of illustration, there is shown a preferred embodiment of the present invention secured to a rotary lawn mower 20 powered by an internal combustion engine 21 of the conventional design. The engine 21 has a vertically disposed crankshaft 22 at one end of which is secured a blade 23 with the turning mechanism of the present invention, generally designated by numeral 24, secured to its other end. The turning device 24 is supported in operable position with respect to the engine 21 by means of legs 27 or the like on the metal dust cover 25 of mower 20. The legs 27 may be secured to the turning mechanism 24 and the dust cover 25 in any convenient manner.

Basic Element (1)

Referring to FIG. 3, a more detailed description of the preferred embodiment of the turning mechanism 24 of FIG. 1 will be given. The Basic Element (1) of the turning mechanism 24 is comprised of case 26 which is mounted stationary with respect to the engine mount by means of legs 27, as has heretofore been described. A spring shaft 29 is rotatably mounted within the case in any convenient manner and extends therefrom. In the embodiment specifically illustrated, the shaft is rotatably mounted by a bearing which is provided by an annular recess 29b formed within shaft 29 into which is received an inwardly projecting portion 26a of case 26. A spring 28 is operably positioned within case 26 and extends about spring shaft 29. The spring 28 has one of its ends secured to case 26 and the other end is secured to spring shaft 29 in any convenient manner. The spring 28 is arranged in such a manner that when it is wound it can rotate the spring shaft 29 in one direction and when the shaft 29 is rotated in the opposite direction the spring 28 will be rewound or reset. For descriptive purposes the said one direction will be a counterclockwise direction of rotation of shaft 29 when viewed in the relationship shown in FIG. 11.

A locking means is provided whereby the spring shaft 29 may be held stationary with respect to case 26 so that the spring may be wound and held under tension in this position until it is desired to be released and rotate the spring shaft in said one direction. This locking means is provided in the illustrative embodiment by the arrangement of an operating plunger 30 which extends axially into spring shaft 29. A knob 31 is secured to the exposed extremity of plunger 30 to facilitate it being easily grasped by the hand of the operator. An annular groove 32 is provided adjacent the inner extremity of plunger 30. A plurality of balls 34 are mounted in a passageway 33 extending radially outwardly through spring shaft 29 so that when plunger 30 is moved downwardly as viewed in FIG. 3 balls 34 will move radially inwardly due to the tapering surface 32a until they seat in groove 32. When the plunger is moved upwardly as viewed in FIG. 4 due to the bias of spring 36, the balls are forced radially outwardly by tapering surface 32a so that they will assume the position shown in FIG. 4 and can engage recess 35 in a second internal gear wheel 40. Internal gear wheel 40 is provided with means to prevent it from being rotated

in said one direction by the spring shaft 29 and thereby locking the spring shaft relative to the case. Thus, when the plunger is depressed to the position shown in FIG. 3, balls 34 recede into groove 32 and thereby free spring shaft 29 so that it may rotate in said one direction due to the tension of the spring and when the plunger 30 is returned by spring 36 to the position shown in FIG. 4, spring shaft 29 is locked relative to the case and movement in said one direction cannot result.

Once the operating plunger 30 is depressed, it may be released but will not return to its upward position because the balls 34 will not be displaced outwardly sufficiently to engage recess 35 in member 40 until the speed at which shaft 29 is rotating decreases and approaches the speed at which second internal gear wheel 40 is rotating. It is only under such conditions that spring 36 can urge plunger 30 upwardly with sufficient bias that tapered surface 32a can cam balls 34 into recess 35 thereby locking shaft 29 to internal gear wheel 40. This, of course, locks shaft 29 and gear 40 together without a great deal of strain being exerted on balls 34 or recess 35, and avoids having to hold plunger 30 down throughout the starting cycle.

A means by which a driving connection is made between the spring and rotatable shafts whereby the spring shaft may rotate the rotatable shaft in said one direction is provided by means of a cylindrical housing 37 which is releasably secured to shaft 22 by means of nut 38 so that the housing 37 is carried on engine shaft 22. A plurality of pawls 39 are pivotally mounted within housing 37. The extremity of spring shaft 29 adjacent the engine shaft 22 is provided with a notched surface 29a so as to form a ratchet wherein the pawls 39 may engage. This is most clearly shown in FIG. 11. The pawls 39 are resiliently urged by springs 39a into engagement with the ratchet surface 29a of shaft 29. This arrangement of the pawls 39 permits the shaft 29 to turn the crank shaft 22 in said one direction and will permit the pawls 39 to be disengaged from shaft 29 after the engine is operating under its own power. The pawls of course will be forced outwardly out of disengagement with shaft 29 under such conditions. This arrangement provides an effective drive connection so that the spring shaft may rotate the rotatable shaft in said one direction but not in the reverse direction. The resilient means or springs 39a will force the pawls 39 into engagement with shaft 29 whereby a condition exists so that shaft 29 may rotate shaft 22 upon the engine 21 being stopped.

The engine is started when the spring is wound and under tension and the spring shaft 29 is locked to second internal gear wheel 40. It is started by depressing plunger 30 so that balls 34 recede into groove 32 thereby unlocking shaft 29 from gear wheel 40 whereby shaft 29 is rotated by spring 28 in said one direction. Such rotation is transmitted to shaft 22 through the drive connection means comprised by pawls 39 in cylindrical housing 37 engaging the ratchet surface 29a of shaft 29. This arrangement of the shaft 29 with respect to shaft 22 in the first element is of particular utility in this invention as it is most desirable to rotate shaft 22 by means of shaft 29 at the highest possible rotary speed in order to be able to successfully start even the most balky internal combustion engines with which it is used. Thus, such a direct transmission of torque from the spring 29 to shaft 22 is achieved. Other means for locking shaft 29 relative to case 26 and for providing a drive connection between spring shaft 29 and crankshaft 22 may also be used, as will be apparent to a person skilled in the art.

It is seen that this arrangement of the case and spring shaft 29 permits the spring shaft to extend outwardly from only one side of the case 26 and thereby provide a more compact unit than otherwise possible.

Basic Element (2)

The Basic Element (2) of the turning device of the

present invention is a rewinding means which is connected to the spring shaft whereby the spring shaft may be rotated in a direction reverse to said one direction of rotation, whereby the spring may be rewound. It is preferable that the speed of rotation at which the spring shaft 29 is rotated in a direction to wind the spring 28 is at a greatly reduced rate relative to the speed of rotation at which the rotatable shaft 22 is operating under normal conditions. Such an arrangement provides several advantages, one of which is that there is less loading on the engine during rewinding of the spring and also that there is less danger of breaking the spring when it is rewound at a relatively low rate of speed. The rewinding means is selectively connected to the shaft 22 by means of clutch means interposed therebetween, which will be more fully described hereafter, so that power may be transmitted from the rotatable shaft 22 to the rewinding means.

Referring more particularly to FIGS. 3 and 4, the rewinding means in the embodiment specifically illustrated is shown as an epicyclic gear train which is mounted on the shaft 29. This arrangement provides an extremely compact turning device and avoids using a plurality of shafts to support the rewinding means as was commonly used in earlier known devices. This gear train comprises a plurality of external and internal gear wheels, and eccentric hubs mounted on shaft 29. This train comprises a first eccentric hub 41 rotatably mounted on shaft 29 and connected to the clutch means whereby power from shaft 22 may be selectively transmitted to rotate the eccentric hub 41 on shaft 29. A first internal gear wheel 42 is rotatably mounted on the first eccentric hub 41 and is provided with overlying teeth which mesh with the teeth of a first external gear wheel 43 that is rotatably mounted on shaft 29. First external gear wheel 43 is provided with a second eccentric hub 44 on which is rotatably mounted a second external gear wheel 45. A second internal gear wheel 40 is rotatably mounted on shaft 29 and is provided with overlying teeth which intermesh with the teeth of second external gear wheel 45. Means are provided to prevent the first internal gear wheel 42 and the second external gear wheel 45 from rotating about the spring shaft 29 in said one direction and take the form of dogs 46 and 47. The first internal gear wheel 42 is provided with one more tooth than the first external gear wheel 43 and the second external gear wheel 45 is provided with one less tooth than internal gear wheel 40. With this tooth arrangement and holding the first internal gear wheel 42 and second external gear wheel 45 from rotating about the spring shaft, the direction of rotation of the spring shaft 22 is reversed so that the spring shaft 29 will be rotated in a direction reverse to the said first direction of rotation and the speed at which it is rotated is reduced. This result is obtained because the clutch parts rotate in the same direction as shaft 22, and drive the hub 41 to rotate in said one direction. This rotation of hub 41 causes the first internal gear wheel 42 to oscillate thereon since it is held against rotation in said one direction. This can be readily seen by reference to FIG. 9. The oscillation of first internal gear wheel 42 will rotate the said first external gear wheel 43 in a direction reverse to the said one direction due to the difference in number of teeth on the respective members and because first internal gear wheel 42 is held against angular rotation as can be seen in FIG. 8. Rotation of first external gear wheel 43 on shaft 29 causes the second eccentric hub 44 to oscillate the second external gear wheel 45 thereon because second external gear wheel 45 is held against rotation by dog 47 as is shown in FIGS. 6 and 7. The oscillation of second external gear wheel 45 will rotate second internal gear wheel 40 in a direction reverse to said one direction at a reduced rate of rotation. This arrangement, of course, results in rotation of the spring shaft 29 at a greatly reduced angular rotation and in a direction op-

posite to said first direction at which engine shaft 22 is operating to thereby rewind the spring 28. It is, of course, obvious to those skilled in the art that other methods may be used whereby the direction of rotation between shaft 22 and spring 28 may be reversed and also if desired, that the relative speeds of rotation be greatly reduced. Of course, during rewinding the operating plunger 30 is in the position shown in FIG. 4 whereby the shaft 29 is locked to second pinion 40.

10 A manual rewinding means is provided to reset the spring 28 and takes the form of a handle 48 as shown in FIG. 10 which is rotatably mounted upon a circular hub portion 42a of first internal gear wheel 42. This arrangement permits the handle to be moved back and forth
15 within its limits of travel between the support members 27. A dog 49 is carried on handle 48 in any convenient manner such as by a stud 50, and engages the teeth of second external gear wheel 45. Thus, from FIG. 9 it can be readily seen that operation of the handle in a reciprocal manner will result in dog 49 engaging the teeth of second external gear wheel 45 and rotating it, second internal gear wheel 40 and shaft 29 in a direction reverse to said
20 one direction, thereby rewinding the spring 28.

Of course, the rewinding of the spring 28 is accomplished through the assistance of the rotational speed reduction provided by second external gear wheel 45 and second internal gear wheel 40 as part of the epicyclic gear train and reduces the effort required to rewind the spring 28 manually. This arrangement permits the turning device to be used with internal combustion engines of a rather large horsepower capacity.

Such an arrangement of the epicyclic gear train provides a very convenient method of reversing the direction of the rotation of the shaft 22 whereby the spring shaft 35 29 may be rotated in the proper direction to rewind the spring and also reducing the speed at which it is wound and is one of the important features of the present invention.

Basic Element (3)

40 The clutch means whereby the rewinding means is connected to the shaft 22 is the Basic Element (3) of the present invention and is comprised of clutch parts 51 and 52 having complementary ratchet-like facings 53, which when engaged, will transmit power between such parts.

45 A first clutch part 52 is carried on cylindrical housing 37 and a second clutch part 51 is rotatably mounted on spring shaft 29 and is adapted to move to and from first clutch part 52. The clutch parts 51 and 52 are shown in engagement in FIG. 4. In FIG. 3, clutch part 51 is shown disengaged from clutch part 52. It is obvious from the structure provided that when these clutch parts are engaged a driving connection is produced between the rotatable shaft and the rewinding means whereby power may be transmitted therebetween.

Basic Element (4)

A clutch engaging means is the Basic Element (4) of the present invention and is used to engage and disengage the second clutch part 51 from the first clutch part 52.

60 The clutch engaging means is connected to the spring intermediate its ends and is adapted to engage and disengage the clutch parts in response to movement of the spring as its tension is changed during winding and unwinding whereby said clutch engaging means will engage the clutch parts 51 and 52 as the spring 28 is unwound and will disengage the clutch parts as the spring is wound. This is an important feature of the present invention since the rewinding of the spring is controlled by the spring itself and not by timing devices which were heretofore required.

65 The clutch engaging means is comprised of a shifting fork 54 which is pivotally mounted on case 26 and is provided with a semicircular portion 55 having guide members 56 mounted thereon which are adapted to engage an annular groove 57 formed in clutch part 51.

70 A shifting fork control rod 58 is connected to shifting fork 54.

75 A shifting fork control rod 58 is connected to shifting fork 54.

ing fork 54. The shifting control rod 58, at a position remote from the fork 54, is loosely disposed in a slot 59b in the edge of a disc 59, which disc is pivotally mounted to case 26 by means of stud 60. By reference to FIGS. 12 and 13 it will appear that upon rotation of the disc 59 clockwise, the portion of rod 58 within the said slot 59b will be engaged by the lower side of the slot. The rod being restricted by the pivotal mounting of the fork 54 to a swinging movement about said pivotal mounting in a plane at right angles to said mounting, the portion of said rod in said slot will be moved radially toward the shaft 29. Referring to FIG. 2, it will be seen that this movement will result in counterclockwise movement of the fork 54 and engagement of clutch parts 51 and 52. Rotation of the disc 59 counterclockwise will produce the opposite effect and disengage clutch parts 51 and 52. A pin 61 is secured to spring 28 intermediate its ends and extends out of case 26 through an opening 62 provided therein (see FIGS. 2 and 12). As can best be seen in FIG. 14, pin 61 is received in notch 59a in disc 59, whereas control rod 58 is received in notch 59b. It is evident that the spring will move as it is wound or unwound; therefore, its movement is applied to circular disc 59 to rotate it counterclockwise or clockwise by means of pin 61 which moves with a substantial component radially inwardly or outwardly of the shaft 29 in response thereto and thereby moves control rod 58, causing shifting fork 54 to pivot and move clutch part 51 to and from engagement with clutch part 52. Thus, with the spring fully wound the shifting fork assumes the position shown in FIGS. 2 and 3. As the spring is unwound, the disc 59 is moved in a clockwise direction as seen in FIGS. 12 and 13 to the position shown in FIGS. 4, 12 and 13, which results in shifting fork 54 being moved by control rod 58 counterclockwise on its pivotal mounting as seen in FIG. 2 to a position whereby clutch part 51 is engaged with clutch part 52. Thus, it can be seen that the movement of the spring 28 as it unwinds and winds causes and is responsible for the action of the shifting fork 54 in moving clutch part 51 into and out of engagement with clutch part 52 through the mechanism of disc 59.

Preferably, pin 61 is secured to spring 28 adjacent its end that is secured to case 26. Such an arrangement is advantageous in that the outer extremity of the spring has much greater and faster movement during its initial unwinding than do the other positions of the spring, especially those that are secured to spring shaft 29. Thus, only a relatively minor unwinding of the spring need occur to result in the engagement of the clutch part 51 and 52 with a sudden or snap action, which, of course, results in a very positive engagement of the clutch parts 51 and 52, and thereby prevents chattering about their ratchet faces 53. The spring shaft 29 is unlocked from second internal gear wheel 40 when the spring 28 is unwinding and therefore the winding means, comprised of the epicyclic gear train heretofore described, is free to rotate on shaft 29 and therefore may be considered "free-wheeling" so that its inertia is extremely low. Therefore, clutch member 51 may be engaged with clutch part 52 to drive the rewinding means even though the turning mechanism is in the process of rotating shaft 22 in said one direction to start the engine. Upon the engine starting, the shaft 22 is, of course, operated by the power of the engine and results in the pawls 39 being forced away from engagement with the shaft 29, which allows the spring shaft 29 to rotate freely thereby unwinding the spring 28. When the speed of shaft 29 is only slightly different from the speed of the second internal gear wheel 40 of the rewinding means, balls 34 will lock shaft 29 to second internal gear wheel 40, as has heretofore been described. As clutch parts 51 and 52 are engaged under these conditions, the power of shaft 22 will be applied through the rewinding means, which reverses the direc-

tion of rotation and reduces the speed of rotation, to spring shaft 29 so as to rewind spring 28.

As spring 28 is being rewound, the pin 61 carried by the spring is being moved radially inward toward shaft 29, as viewed in FIG. 12, and moves circular disc 59 in a counter clockwise direction, causing shifting rod 58 to move the shifting fork 54 in a direction whereby clutch part 51 is disengaged from clutch part 52. However, during rewinding the movement of the outer extremity of the spring is much slower than it is during unwinding, and, therefore, there is a tendency for the ratchet face 53 of clutch parts 51 and 52 to chatter as the spring approaches its desired tension. To prevent such undesired chattering of the clutch parts 51 and 52, a snap action means is connected to the clutch means whereby the disengagement of the second clutch part 51 from the first clutch part 52 is restrained until a predetermined amount of tension has been stored in spring 28 and applied to the snap action means to overcome the restraining effect, at which time clutch part 51 is freed to move rather suddenly and results in a snap action movement of the shifting fork 54 to disengage clutch part 51 from clutch part 52.

The snap action means can best be seen in FIGS. 12, 13 and 14. The snap action means is provided by one or more balls 63 which were carried in openings 64 in disc 59 engaging recesses in case 26. A spring plate 65 is provided to press balls 63 against the case 26 with a pre-selected desired degree of bias that is determined by how tightly stud 60 is tightened against case 26. The case 26 is provided with one or more recesses 66 (shown in FIG. 12 wherein plate 65 and disc 59 are broken away to expose same) in its surface wherein balls 63 may be received when the shifting fork 54 has engaged clutch parts 51 and 52 and the disc 59 is moved to a counter clockwise position by pin 61 as the spring is unwound. It is evident that this is a simple detent means which will result in disc 59 being restrained from moving in a clockwise direction due to engagement of ball 63 with recess 66 until the tension of the spring 28 as it is rewound increases and can overcome the restraining effect created by the biasing of ball 63 into recess 66 by spring plate 65. Upon such occurrence, the disc 59 is free to move with great suddenness or with a snap action, thereby allowing shifting fork 54 to disengage clutch part 51 from clutch part 52 with a snap action.

Other recesses may be provided in cover 26 whereby the engagement of the clutch parts may be effected with a snap action as the spring is unwound where the pin 61 is connected to the spring 28 at positions intermediate its ends and other than adjacent its end secured to case 26. The snap action mechanism may take other forms than that specifically illustrated herein, such that a snap action movement is produced in either engagement or disengagement of the clutch parts, or in both functions.

The turning device operates in the following manner. With the spring unwound and the engine 21 inoperative, the handle 48 is rocked to rotate second external gear wheel 45, second internal gear wheel 40 and spring shaft 29 to rewind the spring 28 to any desired initial tension.

With the spring rewound, plunger 30 is depressed and released whereon shaft 29 is freed to be rotated very quickly by spring 28. Rotation of shaft 29 is transmitted to engine shaft 22 and usually results in engine 21 being started. Should the engine fail to start, the spring may be readily rewound by means of handle 48.

Once the engine has started, power is transmitted from shaft 22 to the rewinding means and the plunger 30 returns to its original position which results in shaft 29 being rotated in a proper direction to rewind the spring. Upon the spring being rewound, the clutch means are disengaged with a snap action and the turning device is ready for the next cycle of starting engine 21. The rewinding of the spring is completely automatic when the engine starts.

The turning device of the present invention can be readily installed on existing devices as is apparent from the drawings and the description herein.

Thus, there has been provided herein a novel turning device for a rotatable shaft in which the spring is wound and unwound from the same end and which utilizes a single spring shaft extending from only one side of the case which houses the spring. The rewinding means for restoring the spring to a wound condition is simple yet compact and efficient. Further, the functioning of the rewinding means is controlled by the movement of the spring as its tension is changed during winding and unwinding, thus completely dispensing with any complex timing device such as heretofore required to control the rewinding of the spring. If desired, snap action means are provided to prevent the clutch means used to transmit power to the rewinding means from being damaged through a lack of positive engagement and disengagement.

From the foregoing it will be seen that this invention is one well adapted to attain all of the ends and objects hereinabove set forth, together with other advantages which are obvious and which are inherent to the device.

It will be understood that certain features and sub-combinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

The invention having been described, what is claimed is:

1. A turning device for a rotatable shaft comprising, an anchor with respect to which said shaft is rotatable, a spring shaft rotatably mounted with respect to said anchor, a spring positioned and extending about the spring shaft having one end attached to the spring shaft and the other end secured to the anchor, the spring when wound adapted to rotate the spring shaft in one direction, means by which a driving connection is made between the spring shaft and such rotatable shaft for rotating the last-mentioned shaft in said one direction, rewinding means connected to the spring shaft for rotating the spring shaft in a direction reverse to said one direction to wind said spring, clutch means interposed between said rewinding means and the rotatable shaft, said clutch means when engaged providing a drive connection between said rewinding means and the rotatable shaft, and clutch engaging means connected to the spring intermediate its ends and adapted to engage and disengage said clutch means in response to movement of the spring as its tension is changed during winding and unwinding whereby said clutch engaging means engages said clutch means as the spring is unwound and disengages said clutch means as the spring is wound.

2. A turning device as in claim 1, wherein said clutch engaging means is connected to the spring adjacent the end of the spring secured to the case.

3. A turning device for a rotatable shaft comprising an anchor with respect to which said shaft is rotatable, a spring shaft rotatably mounted with respect to said anchor, a spring positioned and extending about the spring shaft having one end attached to the spring shaft and the other end secured to the anchor, the spring when wound adapted to rotate the spring shaft in one direction, means by which a driving connection is made between the spring shaft and such rotatable shaft for rotating the last-mentioned shaft in said one direction, rewinding means connected to the spring shaft for rotating the spring shaft in a direction reverse to said one direction to wind said spring, clutch means interposed between said rewinding means and said rotatable shaft, said clutch means when engaged providing a drive connection between said

rewinding means and the rotatable shaft, clutch engaging means connected to the spring intermediate its ends and adapted to engage and disengage said clutch means in response to movement of the spring as its tension is changed during winding and unwinding, and a snap action means connected to the clutch means for restraining disengagement of said clutch means until its restraining action is overcome by spring tension whereby said clutch engaging means disengages said clutch means with a snap action upon the tension of the spring increasing sufficiently to overcome the restraining action of said snap action means as the spring is wound.

4. A turning device as in claim 3, wherein said clutch engaging means is connected to the spring adjacent the end of the spring secured to the case.

5. A turning device as in claim 3 wherein said snap action means comprises a detent means to restrain engagement of the clutch engaging means until its restraining action is overcome by a predetermined increase in tension of the spring whereby the detent means releases thereby permitting engagement of the clutch means with a snap action.

6. A turning device for a rotatable shaft comprising, a case stationary with respect to said rotatable shaft, a spring shaft rotatably mounted in the case and extending therefrom, a spring positioned within the case and extending about the spring shaft having one end attached to the spring shaft and the other end secured to the case, the spring when wound adapted to rotate the spring shaft in one direction, means by which a driving connection is made between the spring shaft and such rotatable shaft for rotating the last-mentioned shaft in said one direction, rewinding means connected to the spring shaft for rotating the spring shaft in a direction reverse to said one direction to wind said spring, clutch means interposed between said rewinding means and the rotatable shaft, said clutch means when engaged providing a drive connection between said rewinding means and the rotatable shaft, clutch engaging means connected to the spring intermediate its ends and adapted to engage and disengage said clutch means in response to movement of the spring as its tension is changed during winding and unwinding whereby said clutch engaging means engages said clutch means as the spring is unwound and disengages said clutch means as the spring is wound, and a snap action means connected to the clutch means for restraining the engagement and disengagement of the clutch means until such restraining action is overcome by spring tension whereby said clutch engaging means engages the clutch means with a snap action upon the tension of the spring decreasing sufficiently to overcome such restraining effect as the spring is unwound and disengages the clutch means with a snap action upon the tension of the spring increasing sufficiently to overcome the restraining effect of the snap action means as the spring is wound.

7. A turning device as in claim 6 wherein said clutch engaging means is connected to the spring adjacent the end of the spring secured to the case.

8. A turning device as in claim 6 wherein said snap action means comprises a detent means to restrain engagement of the clutch engaging means until its restraining action is overcome by a predetermined increase in tension of the spring whereby the detent means releases thereby permitting engagement of the clutch means with a snap action.

9. A turning device for a rotatable shaft comprising a case stationary with respect to said rotatable shaft, a spring shaft rotatably mounted in the case and extending therefrom, a spring positioned within the case and extending about the spring shaft having one end attached to the spring shaft and the other end secured to the case, the spring when wound adapted to rotate the spring shaft in one direction, means by which a driving connection is made between the spring shaft and such rotatable shaft

for rotating the last-mentioned shaft in said one direction, rewinding means connected to the spring shaft for rotating the spring shaft in a direction reverse to said one direction to wind said spring, clutch means interposed between said rewinding means and said rotatable shaft when engaged to transmit power from the rotatable shaft to the rewinding means, said clutch means comprising a first clutch part carried by the rotatable shaft, and a second clutch part rotatably mounted on said spring shaft, said second clutch part being slidably mounted on said spring shaft for movement to and from said first clutch part; clutch engaging means comprising a shifting fork pivotally mounted on the case and adapted to move said second clutch part, and said shifting fork connected to the spring adjacent the end of the spring secured to the case and adapted to move said second clutch part into and out of engagement with said first clutch part in response to movement of the spring as its tension is changed during winding and unwinding, a snap action means connected to the clutch means for restraining movement of said second clutch part out of engagement with said first clutch part until its restraining action is overcome by spring tension, whereby the shifting fork moves the second clutch part into engagement with the first clutch part upon the tension of the spring decreasing as the spring is unwound and moves the second clutch part out of engagement with the first clutch part with a snap action upon the tension of the spring increasing sufficiently to overcome the restraining action of said snap action means upon the spring being wound.

10. A turning device as in claim 9 wherein said rewinding means is an epicyclic gear train which comprises, a first eccentric hub carried by said second clutch part, a first pinion rotatably mounted on said eccentric hub, a first wheel rotatably mounted on the spring shaft and adjacent to said first pinion and having teeth intermeshed therewith, said first wheel having at least one tooth less than said first pinion, a second eccentric hub carried by said first wheel, a second wheel rotatably mounted on said eccentric hub of said first wheel, a second pinion carried by said spring shaft adjacent to said second wheel and teeth intermeshed therewith, said second pinion having at least one tooth more than said second wheel, means to prevent the first pinion and second wheel from rotating about the spring shaft, rotation of the second clutch part in said one direction causing said first pinion to oscillate on the first eccentric hub and thereby said first pinion driving said first wheel in a reverse direction to said one direction at a reduced angular rotation, rotation of said first wheel causing said second wheel to oscillate on the second eccentric hub and thereby said

second wheel driving said second pinion at a reduced angular rotation to rotate the spring shaft and wind the spring.

11. A turning device as in claim 9 wherein said snap action means comprising, a movable member connected to said clutch means and adapted to be moved to a first position when the second clutch part is disengaged from the first clutch part and to a second position when the clutch parts are engaged, a stationary member that is stationary with respect to said movable member, detent means carried by one of the members and detent receiving means carried by the other of said members, said detent and detent receiving means engaging when the movable member is in said second position and thereby restraining movement of said movable member to the first position until the tension of the spring increases sufficiently upon the spring being wound to overcome such restraining action whereby said movable member is moved from the second position to the first position with a snap action.

12. A turning device for a rotatable shaft comprising an anchor with respect to which such shaft is rotatable, a spring shaft rotatably mounted with respect to said anchor, a spring having one part secured to the spring shaft and another to the anchor, the spring when wound adapted to rotate the spring shaft in one direction, means by which a driving connection is made between the spring shaft and such rotatable shaft for rotating the last-mentioned shaft in said one direction, rewinding means connected to the spring shaft for rotating the spring shaft in a direction reverse to said one direction to wind said spring, clutch means interposed between said rewinding means and the rotatable shaft, said clutch means when engaged providing a driving connection between said rewinding means and the rotatable shaft, clutch engaging means connected to said clutch and positioned to be acted upon by said spring in proportion to the degree of winding thereof for engaging and disengaging the clutch when said spring has been wound to a predetermined degree, and snap action means connected to the clutch means for resisting disengagement thereof until its resisting action is overcome by the increasing tension of said spring as it becomes more fully wound.
